UNITED STATES PATENT OFFICE.

CHARLES WIEBKE, OF NEWARK, NEW JERSEY.

PRESSING-ROLLER.

No. 902,788.

Specification of Letters Patent.

Patented Nov. 3, 1908.

Application filed August 24, 1906. Serial No. 331,881.

To all whom it may concern:

Be it known that I, CHARLES WIEBKE, a citizen of the United States, residing at Newark, in the county of Essex and State of New Jersey, have invented certain new and useful Improvements in Pressing-Rollers, of which the following is a specification, reference being had therein to the accompanying drawings, forming a part thereof.

10 My invention relates to rollers such as are employed for fluting or crimping or pressing fabrics and fibrous material, and has for its objects simplicity and economy of construction, the avoidance of any strains from unequal expansion and contraction of the parts, and increased efficiency of operation.

Other objects of my invention will appear from the following description.

I will now describe the apparatus embodying my invention illustrated in the accompanying drawings and will thereafter point out my invention in claims.

Figure 1 is a vertical longitudinal central section showing a pair of rollers, a frame and bearings for the rollers and means for heating the rollers. Fig. 2 is a longitudinal central section of one of the rollers. Fig. 3 is a cross-section of the roller taken on a plane indicated by the line 3—3, in Fig. 2. Fig. 4 is a cross-sectional view of the roller taken on a plane indicated by the line 4—4, Fig. 2.

The two rollers shown in Fig. 1 are of identical construction except that the lower roller is extended to carry a motion receiving gear 30. This lower roller is separately shown in Figs. 2, 3 and 4. Each roller is made up of two parts, an outer tubular part 1 and an inner supporting part or core 2.

The outer part 1 is a cylindrical seamless tube, preferably of brass, and is rigidly secured upon the middle portion of the core in the manner hereinafter described. The core is preferably of cast iron and is provided with journals 3 and 4 at its ends.

45 A series of ports or openings through the core is provided between the journals of the core so that this part of the core is a grated frame or grid with air supply ports for affording a proper air supply to the heating flames and flame openings to permit direct action by the flames upon the inner surface of the outer tube 1 of the roller. As shown, there are 50 four sets of holes, of which the two end sets 6, 6, located in proximity to the journals, are the air supply ports, and the other two sets 5, 5, externally covered by the outer tube,

are the flame openings for direct access of the flames to the tube. The air supply ports serve also as a means for keeping down the temperature of the journals. The provision of these ports and openings leaves the structure of the core about these openings in the form of a grid composed of four longitudinal bars and three annular bars or rings. These annular rings 7 are of slightly larger diameter than the portion having the longitudinal bars, and one of them, shown as the end ring to the right in Figs. 1 and 2, is turned down to a diameter minutely in excess of the inner diameter of the tube 2 so that the tube must 60 be heated to permit it to be passed over this ring. The other two rings 7 are turned down to a diameter minutely less than the inner diameter of the tube 2 so that the tube 65 will slip over these two rings and will have a 70 loose fit thereon.

In assembling the parts it is necessary to heat the end of the tube which is to slip over the end ring of larger diameter, and upon the cooling of the parts, the tube will be held 75 upon this ring by a shrinkage fit. To further rigidly secure the tube upon this ring of 80 larger diameter, a lock-pin 8 is inserted radially through the tube and core. While the tube is thus rigidly secured to one of the 85 rings 7, it is only loosely fitted upon the other rings 7 and may therefore freely expand and contract under the varying conditions of heat imparted to it in use and the core may also freely expand and contract 90 and the unequal expansion and contraction of the tube and core will not cause any strain upon either part.

In the manufacture of the roller the journals 3 and 4 may first be turned, the tube 2 95 then shrunk and pinned upon the core, and if the roller is to be provided with grooves or flutings, the grooves or flutings may then be cut in the tube. The tube, being of drawn metal, will be free from blow holes or other inherent concealed defects such as are frequent in cast parts and would require the entire roller to be discarded when disclosed in cutting the grooves or flutings.

The journals 3 and 4 are shown in Fig. 1 100 as arranged to rotate in brasses or journal boxes 9 and 10 of usual construction, held in vertical slots or openings formed in the pedestals 11 and 12. The upper journal boxes 9 are pressed downward by the helical 105 springs 13 bearing upon the tops of the boxes and having their tension regulated by set-

screws 14, which are screwed into the bars or yokes 15 at the tops of the pedestals.

I will now describe the means shown for heating the hollow rollers.

5 A flue casting 16 is secured to the pedestal 11 and is provided with bosses 17, the axes of which are coincident with the respective axes of the hollow rollers. The bosses serve as supports for central pipes 18 which extend inward horizontally from their outer connections with the cylindrical cap 19. This cap is closed at its upper end and provided at its lower end with a bore 20 of smaller diameter than that of the chamber of the cap 15 and into which the fuel feed-pipe 21 fits. The lower portion of this cylindrical cap is provided with a draft or air inlet 22 through which air is drawn by the fuel, thus making a Bunsen burner. The horizontal pipes 18 extend into the hollow rollers and are closed at their ends, and are provided on their upper portions with burner apertures 23.

To provide means of escape for the heat and gases resulting from the combustion of 25 the fuel supplied by the pipes to the burners just mentioned, the bores of the roller journals 3 adjacent to the casting 16 open into the vertical passage of the casting. The top portion 24 of this passage is threaded and 30 into it is fitted a vertical pipe 25 carrying the heated gases upward and away from the operator. The heat as it passes towards the flue causes fresh air to be drawn through openings of the journals at the right hand 35 ends of the hollow rollers, creating a draft thereby, and also causes fresh air to be drawn through the ports or openings 6 in proximity to the ends of the tubes 1.

It is obvious that various modifications 40 may be made in the construction shown and

above particularly described within the principle and scope of my invention.

I claim as my invention:

1. A pressing roller comprising a hollow core and a tube forming the working surface 45 of the roll, mounted on the core and fitting it tightly for a short part of its length and loosely for the rest of its length.

2. A pressing roller comprising a hollow core having a plurality of bearing rings, and 50 a tube forming the working surface of the roll, mounted on the rings and fitting one ring tightly and the others loosely.

3. A pressing roller comprising a tube forming the working surface of the roller, and 55 a core consisting of a plurality of longitudinal bars forming a grid and bearing rings fixed to the bars and of greater diameter than the grid, the bearing rings engaging the inner surface of the tube to support the same. 60

4. A pressing roller comprising a tube forming the working surface of the roller, and a core consisting of a grid of less diameter than the tube and a plurality of bearing rings of greater diameter than the grid, one 65 of said rings fitting the tube tightly and the others loosely.

5. A pressing roller comprising a tube of refractory material forming the working surface of the roller, and a hollow core, on which 70 the tube is mounted, fitting the tube tightly at only a limited part of the length thereof and having open ends projecting beyond the ends of the tube to form journals.

In testimony whereof I have affixed my 75 signature in presence of two witnesses.

CHARLES WIEBKE.
